UNITED STATES PATENT OFFICE.

KRAFT BOOTH, OF PHILADELPHIA, PENNSYLVANIA, ASSIGNOR TO
GILLINDER & SONS, INC., OF PHILADELPHIA, PENNSYLVANIA.

DESIGN FOR AN ARTIFICIAL-LIGHT SHADE OR GLOBE.

No. 38,684.

Specification for Design.

Patented July 16, 1907.

Application filed June 22, 1907. Serial No. 380,369. Term of patent 14 years.

To all whom it may concern:

Be it known that I, KRAFT BOOTH, a citizen of the United States, and a resident of the city of Philadelphia, in the county of Philadelphia and State of Pennsylvania, have invented a new, original, and ornamental Design for an Artificial-Light Shade or Globe, of which the following is a specification, reference being had to the accompanying drawing, in which—

Figure 1 is a view in side elevation of an artificial light shade or globe, showing my design. Fig. 2 is a perspective view, showing the same in a reverse position.

The shade or globe is of transparent glass,

the interior surface being smooth and the exterior surface, except where the design appears, is ground or frosted. The design, indicated by full lines, is in intaglio on the exterior surface of the shade or globe, and is visible on the interior thereof as indicated by dotted lines in Fig. 2.

I claim as my invention:—

The ornamental design for an artificial light shade or globe, as shown and described.

KRAFT BOOTH.
